UNITED STATES PATENT OFFICE.

KARL SANDERS, OF RUGBY, NORTH DAKOTA.

ALTERNATING ROTARY GEARING.

1,199,308.

Specification of Letters Patent. Patented Sept. 26, 1916.

Application filed May 3, 1915. Serial No. 25,398.

To all whom it may concern:

Be it known that I, KARL SANDERS, a citizen of the United States, residing at Rugby, in the county of Pierce and State 5 of North Dakota, have invented certain new and useful Improvements in Alternating Rotary Gearing, of which the following is a specification.

This invention relates to washing machines, and particularly to the class that 10 comprises a horizontally disposed reciprocating cylinder.

The object of my invention is to produce 15 means by which the cylinder may be rotated in a given direction for a certain number of revolutions, then a reverse motion for approximately the same number of revolutions, both directions being obtained from a shaft that is constantly driven in one direction and which forms a part of the washing machine mechanism.

In producing my machine I have provided for the motions referred to above, 20 employing fewer parts than any machine 25 on the market of which I am aware, and one of the objects of my invention is to do this character of work with a device constructed of very few parts.

In the drawings forming part of this 30 specification: Figure 1 is an end elevation of a washing machine with my invention applied thereto. Fig. 2 is a plan view of the mechanism shown in Fig. 1. Fig. 3 is a transverse sectional view through the cylinder of the 35 washing machine. Fig. 4 is an end elevation with part of the frame and the worm gear removed. Fig. 5 is a detail view of the rocking lever, and Fig. 6 is a detail view of the worm gear showing its operating cam.

40 Like characters of reference designate corresponding parts in the several figures of the drawings.

In the drawings I have shown the outside 45 cylinder 1 and the inside cylinder 2 of an ordinary washing machine, the same being mounted upon a frame 3, said frame being extended at one end to form a rectangular support for my gearing mechanism. The inner drum 2 is mounted upon pintles in the 50 ends of the outer drum, one of said pintles being extended and having mounted thereon a large bevel gear 5. Meshing with the gear 5 are bevel pinions 6 and 7, each of which is feathered at 8 upon a shaft 9 suitably 55 mounted in bearings secured to the frame 4. The shaft 9 is designed to be constantly

driven in a given direction and is provided with a pulley 10 which may be any of the ordinary jaw clutch type and to which any suitable belting may be applied. The shaft 60 9 has secured near its central portion a worm 11, said worm engaging a worm gear 12 provided with a cam block 14 designed to move a rocking lever 15 upon its pivot 16 secured to the frame 4. The lever 15 is 65 provided with an opening 17, the sides of which are formed into cam surfaces 18, said cam surfaces designed to be alternately engaged by the cam block 14 on the gear 12 during the course of its rotation. The rocking lever 15 has secured thereto pins 19 which engage the vertical slots 20 in the 70 ends of reciprocating bars designed to slide in suitable guides mounted upon the frame 4. The reciprocating bars 21 have adjustably secured to them adjacent their outer 75 ends yokes 22, said yokes fitting into grooves 23 in the hubs of the pinions 6 and 7. The frame 4 is provided with bearings 24 which embrace the shaft 9 on each side of the 80 worm 11, thereby positively preventing any longitudinal movement of the worm 11 with respect to the frame 4 upon which the gear 12 and the rocking lever 15 are pivoted. The fact that the cams 18 on either side of 85 the rocking lever 15 are exactly alike insures the rotation of the drum 2 a given number of times in either direction, due to the shifting of the bevel pinions 6 and 7 through the 90 instrumentality of the rocking lever 15 and the slide bars 21.

The operation of my device is as follows: The shaft 9 being constantly driven in one direction and the bevel pinion 7 engaging the gear 5, as shown in Fig. 1, will drive the 95 washing machine cylinder in a given direction. During this operation the gear 12 is being constantly rotated by the worm 11 and its cam block will swing around and operate against the lever 15 until said lever 100 assumes the position shown in Fig. 4 of the drawings, when the pinion 7 will have become disengaged and the pinion 6 engaged with the gear 5, thereby rotating the washing machine cylinder in an opposite direction to the one it would rotate in when the parts are as shown in Fig. 1 of the drawings.

I do not confine myself to the exact details of construction as shown in the drawings, as any skilled mechanic may make 110 numerous slight modifications without de-

parting from the spirit of my invention or the scope of the claims.

Having thus described my invention, what I claim is:

- 5 1. A device for imparting alternating rotary motion, comprising a bevel gear attached to the rotating member, said gear being designed to mesh with pinions feathered upon a constantly rotating shaft, a rocking lever provided with adjustable rods for shifting said pinions, said lever being actuated by a cam driven by a worm on the constantly rotating shaft.
- 10 2. A device for imparting alternating rotary motion, comprising a bevel gear attached to the rotating member, said gear being designed to mesh with pinions feathered upon a constantly rotating shaft, a rocking lever provided with adjustable rods for shifting said pinions and means carried by the shaft for rocking said lever.
2. A device for imparting alternating rotary motion, comprising a bevel gear attached to the rotating member, said gear being designed to mesh with pinions feathered upon a constantly rotating shaft, a rocking lever provided with adjustable rods for shifting said pinions and means carried by the shaft for rocking said lever.

Copies of this patent may be obtained for five cents each, by addressing the "Commissioner of Patents, Washington, D. C."

tached to the rotating member, said gear being designed to mesh with pinions feathered upon a constantly rotating shaft, a rocking lever provided with adjustable rods for shifting said pinions, said lever being actuated by a cam driven by a worm on the constantly rotating shaft.

In testimony whereof I affix my signature in presence of two witnesses.

KARL SANDERS.
